ELECTRICAL CONTROL SYSTEM

Danilo Santini, Tenafly, N. J., assignor to Westinghouse Electric Elevator Company, Jersey City, N. J., a corporation of Illinois

Application April 4, 1940, Serial No. 327,819

11 Claims. (Cl. 172—152)

My invention relates to electrical control systems of the variable voltage or Ward-Leonard type and more particularly to control systems of this character which embody regulating apparatus and which are especially adapted for the operation of elevator hoisting motors.

One object of my invention is to provide a variable voltage control system which may be constructed, installed, operated, and maintained in operation at a lower cost than the cost of the variable voltage control systems heretofore provided and to thereby provide for the economical use of variable voltage control systems for smaller installations than has heretofore been practical from a cost standpoint.

Another object is to provide a variable voltage control system in which the generator field may be readily controlled to obtain the most desirable regulation and excitation.

20 A further object is to provide a variable control system in which low priced elements may be used and in which some of the elements or accessories heretofore considered as necessary may be eliminated.

25 A still further object is to provide a variable voltage control system for an elevator which will automatically insure the holding of the brake on the elevator motor until the generator is started in operation.

30 For a better understanding of the invention, reference may be had to the accompanying drawings, in which:

Figure 1 is a diagrammatic representation of an elevator installation embodying my invention;

35 Fig. 2 is a diagrammatic representation, in what is known as the straight line style, of the control system for operating the elevator car shown in Fig. 1;

Fig. 2A is an explanatory illustration of the 40 relays embodied in the control system of Fig. 2. The illustration of the relays in Fig. 2A shows them with their coils and contact members disposed in horizontal alignment with their positions in the straight line circuits of Fig. 2 so that the identification of any relay and the position of its coil and its contact members in the straight line circuits may be readily determined; and

Fig. 3 is a diagrammatic representation of the 50 regulator illustrated in Fig. 1 and the application of its four field windings to its field yoke.

Referring more particularly to Fig. 1 of the drawings, I have illustrated a car C as suspended by a suitable cable 11 which passes over a hoisting drum 12 to a suitable counterweight 13. A

hoisting motor H is provided for operating the hoisting drum by means of a shaft 14 and a worm gear drive 15 to raise and lower the car. A generator G is provided for supplying electrical energy to the hoisting motor.

5 A regulating generator (hereinafter called the regulator) is provided for exciting the generator and regulating its output, and an exciter EX is provided for supplying electrical energy to a control circuit for the elevator and for exciting the hoisting motor. A driving motor M, which may be provided with electrical power from any suitable source such as is represented by the conductors I, II and III, is provided for driving the generator, the regulator and the exciter at constant 15 speed by means of a shaft 16.

An electromagnetic brake B is associated with the shaft 14 for stopping and holding the car when the power to the hoisting motor is cut off. A car switch CS is mounted in the car for use 20 by the car attendant in causing the car to start and stop. The car may be started in the up direction by moving the car switch counter-clockwise and in the down direction by moving it clockwise. When the car switch is centered, it 25 causes the car to stop at the next floor.

I do not care to be limited in the application of my invention to control systems operated by a car switch as it will be evident to those skilled in the art that my invention may be applied to 30 any form of automatic control such as the various push-button control systems.

Fig. 2 illustrates the control system for the car as provided with a pair of supply conductors L+1 and L-1, which are connected, for energization, to the armature EXA of the exciter EX. The field winding EXF of the exciter is connected across the terminals of its armature. The hoisting motor H is provided with an armature HA and a field winding HF, the field winding being 40 connected across the supply conductors L+1 and L-1 for constant energization.

A variable voltage system of control is provided for controlling the operation of the hoisting motor H wherein the hoisting motor armature HA is connected in a closed circuit 17 with the armature GA of the generator G. The generator is provided with a separately excited field winding GF which is connected for energization in a loop circuit 18 with the armature RA of the regulator R, so that the output of the generator, and consequently the speed and direction of operation of the hoisting motor H, may be controlled by controlling the operation of the regulator. An adjustable resistor r2 is connected in 50 55

the circuit of the generator field winding for adjusting the resistance of that circuit to any desired value.

5 The regulator is provided with a self-exciting field winding RCF, a pattern field winding RPF, a differential field winding RDF, and a series field winding RSF, as shown in Figs. 2 and 3.

10 The self-exciting field winding RCF is connected in the loop circuit 18 (Fig. 2) in series with the regulator armature RA and the generator field winding GF. The total resistance of this circuit should be made equal to the volts that the regulator will produce when one ampere flows through its self-exciting field winding. In 15 other words, the circuit is tuned so that perfect regulation will be obtained with no hunting effects.

10 The pattern field winding RPF is disposed to be connected across the supply conductors L+1 20 and L-1 so that the generator voltage and the direction of operation may be controlled by controlling the direction and the value of the current in the pattern field. For a given excitation of the pattern field, the regulator will produce 25 a voltage which will excite the generator field winding GF. As soon as current starts to flow through the generator field winding circuit, the self-exciting field winding RCF excites the regulator to force the current through the generator field winding.

30 A resistor r_3 is connected in the circuit of the pattern field winding to control the value of that winding, and a high speed relay V is provided for short circuiting this resistor when the car is 35 to be operated at its normal high speed.

35 An up direction switch U and a down direction switch D are provided for connecting the pattern field to the supply conductors L+1 and L-1 for causing the car to be operated in the up direction or in the down direction. The direction relays and the high speed relay are controlled by the car switch CS.

40 The differential field winding RDF is connected across the terminals of the generator armature 45 GA. An adjustable resistor r_1 is inserted in series with the differential field winding RDF, so that the value of the differential field winding may be adjusted as desired. This differential field winding and the pattern field winding RPF 50 are adjusted to produce the same and opposite voltage in the regulator for a given excitation of the pattern field. Under these conditions, the generator voltage will always build up to the value indicated by the pattern field. If, for any 55 reason, a drop in voltage takes place in the generator, that causes the strength of the regulator differential field to be less than that of the pattern field, thus creating a voltage differential in the regulator which, by the action of its self-exciting field, will quickly and smoothly bring the generator voltage to the value indicated by the pattern field. In other words, the desired 60 and the actual voltage in the generator will remain the same by reason of the effect of the 65 pattern field and the differential field, regardless of any load condition in the generator tending to change the voltage. This means that by the use of the regulator in the manner indicated, I have not only applied exciting current to the generator field, but also have corrected it for variations 70 in the generator voltage, regardless of whether this variation is caused by armature reaction, saturation, resistance or brush drop.

75 As the current in the generator field increases, the excitation of the regulator differential field

also increases, the strength of this field being such that when the generator reaches the voltage predetermined by the pattern field, the regulator stops building up, maintaining the required generator shunt field excitation to produce the voltage.

80 The regulator series field RSF is connected in series in the loop circuit 17 between the armatures of the generator and the hoisting motor. This field winding is provided to cause the regulator to give the generator field winding sufficient excitation to compensate for the RI drop in the hoisting motor. As the current increases in the armature of the generator, the voltage will rise just enough to overcome the RI drop of 15 this current flowing through the hoisting motor armature. The net result will be a flat speed for the hoisting motor regardless of load and regardless of the selected value of that speed. Anything which tends to disturb this relation will be automatically compensated for by the reaction of the field windings previously described.

85 The electromagnetic brake B is provided with a magnetizing coil 19 which is energized to release the brake when the up or the down direction switch is operated to cause movement of the car in its hatchway. Inasmuch as there is likely to be some lag in the starting of the hoisting motor after a direction switch is operated to start the car by reason of the time it takes the 90 regulator and the generator to build up, the contact members U1 and D1 of the direction switches are provided with dashpots 20 and 21 to delay the operation of the brake coil to release the brake for a predetermined time after the pattern field 95 of the regulator is energized to start the car. The length of the predetermined delay may be adjusted to insure the holding of the car by the brake until the hoisting motor becomes effective.

100 It is believed that the invention will be better understood by the following assumed operation. It will be assumed that the car is standing at its lower terminal and that power applied through the supply conductors I, II and III (Fig. 1) to the driving motor M, thus causing that motor to start 105 rotating the shaft 16, and thus operating the armature EXA of the exciter, the armature GA of the generator and the armature RA of the regulator. The operation of the exciter armature EXA causes the exciter to supply energy to the 110 supply conductors L+1 and L-1, thereby energizing the field winding HF of the hoisting motor H.

115 The rotation of the regulator armature RA does not affect the loop circuit 18 or the generator field winding GF because, as before stated, the self-exciting field winding RCF of the regulator is so designed that it generates just sufficient voltage to send the current through the loop circuit in which the generator field winding is disposed. Hence, the generator field winding is not 120 energized and the generator does not now supply any current to the hoisting motor.

125 As a suitable landing system for causing the car to stop level with the floor when the car switch is centered for a stop, I have illustrated an automatic inductor relay landing system similar to that disclosed in Patent No. 1,884,446, issued October 25, 1932, to K. H. White and G. H. Hearn and assigned to the Westinghouse Electric & Manufacturing Company. The landing system includes a high speed decelerating inductor relay E and a stopping inductor relay F for causing the car to be automatically decelerated from its high speed, and stopped exactly 130

level with the floor at which a stop is to be made. The decelerating inductor relays are mounted on the car in position to be operated by up-direction inductor plates and down-direction plates mounted on the hatchway wall.

The up direction plate UE is for operating the relay E to open its contact members E1. The up direction plate UF is for operating the relay F to open its contact members F1. The down direction plate DE is for operating the relay E to open its contact members E2. The plate DF is for operating the relay F to open its contact members F2. The plates will not operate the relays unless they are energized and the relays are energized only when the car switch is centered to cause the car to stop at a floor.

The contact members of the decelerating inductor relay E are disposed in the circuit of the high speed relay V. The contact members of the supporting relay F are disposed in the circuits of the direction relays U and D. When the car switch is centered for a stop, it energizes the inductor relays. When relay E is energized and comes opposite its inductor plate, it opens its contact members in the circuit of the high speed relay and thus decelerates the car to landing speed. When relay F is energized and comes opposite its inductor plate, it opens its contact members and thus stops the car at the floor.

It will be assumed now that the attendant in the car moves the car switch CS in counterclockwise direction to cause the car to move upwardly.

Briefly, the movement of the car switch for up direction energizes the up direction relay U which releases the brake B and energizes the pattern field RPF. The energized pattern field RPF causes the regulator R to energize the field GF of the generator, which causes the generator G to generate current to energize the hoisting motor H and thereby move the car upwardly. This operation, in detail, is as follows: The movement of the car switch closes the contact members CS1 and 22 to energize the up direction switch U to effect an upward movement of the car. This circuit extends

L+1, CS, CS1, 22, F1, U, 24, 25, L-1

The energized up direction relay U closes its self-holding contact members U5, closes its contact members U2, U3 and U4, and starts its contact members U1 in closing operation.

The closing of the contact members U2 and U3 energizes the pattern field RPF by the circuit extending

L+1, U2, RPF, U3, r3, L-1

As soon as current starts to flow through the pattern field circuit, the regulator field RCF self-excites the regulator to force current through the generator field. As the current in the generator field increases, the excitation of the regulator differential field RDF also increases, the strength of this field being such that, when the generator reaches the voltage predetermined by the pattern field, the regulator stops building up and maintains the required generator field winding excitation to produce that voltage. The excitation of the generator field GF causes its armature GA to supply the required amount of current for operating the hoisting motor H through the loop circuit 17 which connects the armatures of the generator and the hoisting motor.

The contact members U1 close at the expira-

tion of the predetermined time for which the dashpot 20 has been adjusted, thereby energizing the brake coil 21 to release the brake B to permit the car to move freely by the circuit

L+1, 26, 27, U1, L-1

5

When the up direction switch U was energized and closed its contact members U4, the high speed relay V was energized to close its contact members V1. The closing of the contact members V1 short circuits the portion of the resistor r3 in the circuit of the pattern field winding RPF and thereby increases the energization of that field winding to increase the current supplied by the regulator to the generator field winding, thus causing the car to operate at its normal high speed.

If for any reason the loading on the car affects the hoisting motor sufficiently to cause a drop in the voltage of the generator, the strength of the regulator differential field will be less than that of the pattern field and the voltage differential will be set up in the regulator, which by the action of its self-exciting field, will quickly and smoothly bring the generator voltage to the value indicated by the controller or pattern field.

Furthermore, as stated before, the regulator series field winding RSF will cause the regulator R to give the generator field winding GF sufficient excitation to compensate for the RI drop in the hoisting motor H and the net result will be a constant speed for the hoisting motor regardless of the load and regardless of the selected value of that speed, and anything which tends to disturb this relation will be automatically compensated for by the reaction of the field windings as previously described.

The car is now moving up the hatchway at its normal high speed.

It will be assumed now that the car approaches a floor at which the attendant desires to make a stop, and that he thereupon centers the car switch CS to cause the car to stop at the desired floor.

Briefly, the centering of the switch CS energizes the decelerating relay E, which, when it arrives at the decelerating plate UE, deenergizes the speed relay V to decelerate the car. The deenergized relay V energizes the stopping relay F which, when it arrives at the stopping plate UF, deenergizes the up direction relay, which, in turn, deenergizes the pattern field RPF to stop the hoisting motor and apply the brake B to land and hold the car at the floor.

This operation, in detail, is carried out as follows: The centering of the car switch opens its contact members 22 and CS1, but the up direction switch remains energized because of its self-holding contact members U5. However, the centering of the car switch closes its contact members CS1 and 28, thereby energizing the decelerating inductor relay E to effect deceleration of the car from its normal high speed to its stopping speed by the circuit

L+1, CS, CS1, 28, E, U6, L-1

65

The energized inductor relay E does not at once effect the opening of its contact members E1 and E2, but as soon as the car arrives at the up direction inductor plate UE, that plate operates the relay to open its contact members E1, thereby de-energizing the high speed relay V, which in turn opens its contact members V1 and thereby reinserts the resistor r3 in circuit with the pattern field RPF. The inclusion of the resistor r3 in this

70

75

field winding decreases its energization and thereby causes a corresponding decrease by the regulator R of the energization of the loop circuit 18 including the generator field winding GF. The 5 decrease in the energization of the generator field winding causes the generator armature to supply less current to the hoisting motor and thereby decreases the speed of the car.

It should be noted here that the effect of the 10 decreased current flowing in the loop circuit 17 causes the differential field winding RDP of the regulator to be so changed in energization that it cooperates with the pattern field to cause the regulator to quickly and smoothly bring the generator voltage down to the value indicated by the 15 pattern field.

When the high speed relay V was deenergized, it closed its back contacts V2 and thereby completed a circuit for energizing the coil of the 20 stopping inductor relay F, by the circuit

L+1, CS, CS1, 28, F, V2, U8, L-1

It will be assumed now that the car arrives 25 within stopping distance of the floor, at which the stop is to be made, and thus brings the inductor relay F opposite its stopping inductor plate UF. The plate causes the relay to open its contact members F1 and thereby deenergize the up direction switch U. The deenergization of the up direction switch U opens its contact members U1, thus deenergizing the brake coil 27 to apply the 30 brake B to hold the car, and at the same time, opens its contact members U2 and U3, thus deenergizing the pattern field RPF. The deenergization 35 of the pattern field causes the regulator to stop supplying voltage to the generator field winding GF, which, in turn, causes the generator armature GA to stop supplying current to the hoisting motor, thereby stopping the hoisting motor. The stopping of the hoisting motor and 40 the application of the brake stops the car at the floor.

The use of the system described has made it 45 possible to build small variable voltage systems at a very low cost, and without the necessity of employing many costly accessories in the way of switches and relays. It will also be noted that the generator series field and generator differential field usually required in the generators of 50 variable voltage systems have been eliminated. The elimination of these two fields from the generator further contributes to the reduction of cost of the whole system.

Another valuable feature of this control system 55 is that the adjustable resistor r1 disposed in series with the regulator field winding RDP, provides a ready control over the rate of acceleration and retardation of the elevator car, which depends on the amount of resistance in series with the differential field. When this resistance is low, the generator voltage builds up or down quickly, and when the resistance is high, the changes are much 60 slower. This is a valuable advantage in elevator control systems involving inductor relays and inductor plates, because with it the inductor plates may be disposed at definite points from the floor for any desired stopping speed and then the resistor may be adjusted to cause the car to decelerate 65 at the correct speed from that plate to arrive at the proper landing speed adjacent to the floor at which the stop is to be made. Heretofore, when the car began to fail to decelerate to the proper landing speed, it was necessary to physically adjust the plate either up or down the hatchway. My improvement provides a big saving in 70

that it permits the plate to be placed at approximately the correct position and then the system adjusted to the position of the plate, it being much more convenient to change the value of the resistor than to enter the hatchway and change the 5 location of the plate.

Although I have illustrated and described only one specific embodiment of my invention, it is to be understood that changes therein and modifications thereof may be made without departing 10 from the spirit and scope of the invention.

I claim as my invention:

1. In a variable voltage system of control, the combination of a motor having a field winding and an armature operable at a plurality of speeds, 15 a power generator having a field winding and an armature driven at approximately constant speed, said generator armature being connected in loop circuit with the motor armature, a regulating generator having an armature and a self-exciting field winding, a second loop circuit including the self-exciting field winding and the armature of the regulating generator and the field winding of the power generator, a second field winding on the regulating generator connected to carry at 25 least a portion of the current flowing in said first named loop circuit, a third field winding on the regulating generator connected across the terminals of the armature of the power generator, and a fourth field winding on the regulating 30 generator connected to an external voltage supply for controlling the output of electrical energy by the regulating generator.

2. In a cascade connection of a pair of generators delivering energy to a motor, a loop circuit 35 between the generators comprising the armature of one generator, a field winding of a second generator and a field winding of the first named generator, said latter winding being so proportioned that one ampere of current flowing in it 40 produces just enough voltage at its associated armature to circulate one ampere through the loop circuit.

3. In a cascade connection of generators for controlling the speed of a motor wherein the 45 armature of one generator excites a second generator field winding to produce voltage on the second generator to thereby circulate current in the armature of said motor, the combination of a field winding on said first named generator 50 connected across the armature of said second named generator, and current regulating means for varying the strength of said field winding for a given armature voltage to thereby produce a plurality of rates of building up and dying down 55 of the speed of said motor.

4. A variable voltage system of control comprising a power generator provided with an armature and a field winding and a motor connected in a loop circuit with said armature, a regulating generator for energizing a field winding of the power generator, said regulating generator having an armature, a series field winding connected to carry at least a portion of the current flowing in the loop circuit connecting the power generator and the motor, a differential field winding connected across the terminals of the power generator armature, a self-exciting field winding connected in loop circuit with the power generator field winding and the regulating generator armature, and a pattern field winding connected to an external supply of electrical energy for controlling the output of electrical energy by the regulating generator to the power generator. 60

5. A variable voltage system of control com- 70

prising a power generator provided with an armature and a field winding, a motor connected in a loop circuit with said armature, a regulating generator for energizing the field winding of the 5 power generator, said regulating generator having an armature, a series field winding connected to carry at least a portion of the current flowing in the loop circuit connecting the power generator and the motor, a differential field winding 10 connected across the terminals of the power generator armature, a self-exciting field winding connected in loop circuit with the power generator field winding and the regulating generator armature and a pattern field winding connected 15 to an external supply of electrical energy for controlling the output of electrical energy by the regulating generator to the power generator, and a controller for varying the amount of electrical energy delivered to the pattern field 20 winding to secure a plurality of predetermined speeds of operation of the motor.

6. In a variable voltage system of control, a motor connected to a load device, a power generator for energizing the motor, said generator 25 having a field winding and a regulating generator for supplying energy to the field winding of the power generator, said regulating generator having a series of field winding connected to carry at least a portion of the current flowing 30 from the power generator to the motor to cause the regulating generator to give the generator field winding sufficient excitation to compensate for the RI drop in the hoisting motor, a pattern field winding connected to an external supply of 35 electrical energy for causing the regulating generator to supply predetermined values of electrical energy to the power generator field winding to cause that generator to deliver power to the motor, a differential field winding connected 40 across the terminals of the power generator armature for balancing the excitation of the pattern field winding, and a self-exciting field winding connected in loop circuit with the field winding of the power generator and the armature of 45 the regulating generator.

7. In a variable voltage system of control, a motor connected to a load device, a power generator for energizing the motor, said generator having a field winding, a regulating generator 50 for supplying energy to the field winding of the power generator, said regulating generator having a series field winding connected to carry at least a portion of the current flowing from the power generator to the motor to cause the regulating generator to give the generator field winding sufficient excitation to compensate for the RI 55 drop in the hoisting motor, a pattern field winding connected to an external supply of electrical energy for causing the regulating generator to supply predetermined values of electrical energy to the power generator field winding to cause that generator to deliver power to the motor, a differential field winding connected across the 60 terminals of the power generator armature for balancing the excitation of the pattern field winding, a self-exciting field winding connected in loop circuit with the field winding of the power generator and the armature of the regulating generator, and a resistor connected in circuit with the differential field winding for adjusting the value of the differential field winding to regulate the rate of deceleration of the motor.

8. In a variable voltage system of control, an 70 exciter for supplying electrical energy to a con-

trol circuit; a motor having an armature and a field winding, said field winding being connected to said control circuit; a power generator having a field winding and an armature, a loop circuit connecting the armature of the power generator to the armature of the motor; a regulating generator for energizing the field winding of the power generator, said regulating generator having an armature, a series field winding connected in said loop circuit in series with the power generator armature and the motor armature, a pattern field winding connected to said supply conductors to give the regulating generator a predetermined amount of electrical energy, a self-exciting field winding connected in loop circuit with the field winding of the power generator and the armature of the regulating generator for causing the regulating generator to deliver a predetermined amount of electrical energy to the power generator field winding, and a differential field winding connected across the terminals of the power generator armature for causing the regulating generator voltage to build up to the value indicated by the pattern field winding; and a driving motor for operating the exciter, the motor armature, the generator armature, and the regulating generator armature at constant speed.

9. A variable voltage control system for an elevator comprising a hoisting motor for operating an elevator car, said motor having an armature and a field winding; an electromagnetic brake for controlling the hoisting motor; a power generator having a field winding and an armature; a loop circuit connecting the motor armature and the power generator armature through which energy may be supplied from said generator to said motor; a regulating generator for energizing the field winding of the power generator, said regulating generator having an armature and a self-exciting field winding connected in loop circuit with the power generator field winding, a series field winding connected between the armature of the generator and the armature of the motor, a differential field winding connected 40 across the terminals of the power generator armature, and a pattern field winding connected to an external supply of electrical energy, said pattern field winding and said differential field winding being designed to produce the same and 50 opposite voltage in the regulator for a given excitation of the pattern field winding; switch means for connecting the pattern field winding to said external supply of electrical energy, and means responsive to operation of said switching mechanism for effecting the release of the electromagnetic brake upon the expiration of a predetermined time after the pattern field is energized.

10. A variable voltage system of control comprising a motor; a power generator having a field winding and an armature for energizing the motor; a regulating generator for energizing the field winding of the power generator, said regulating generator having an armature and a self-exciting field winding connected in loop circuit with the field winding of the power generator whereby electrical energy is supplied to the power generator by the regulating generator, a series field winding connected in series with the power generator armature and the armature of the motor for causing the regulator to control the supply of energy to the motor, a platform field winding for causing the regulating generator to deliver a predetermined amount of elec- 70 75

trical energy to the field winding of the power generator and a differential field winding connected across the terminals of the power generator armature for controlling the effect of the 5 pattern field winding on the regulating generator in accordance with a given excitation of the pattern field; switching means for connecting the pattern field to an external source of electrical energy, a resistor disposed in circuit with 10 said pattern field, and a speed relay responsive to operation of the switching mechanism for controlling the amount of resistance in circuit with the pattern field to determine the speed of the hoisting motor.

15 11. In a variable voltage system of control, a motor, a power generator having a field winding

and an armature for supplying energy to the motor, a regulating generator having an armature for supplying energy to the power generator field winding, means for causing the generators to operate at approximately constant speed, and 5 a plurality of field windings for the regulating generator, including a self-exciting field winding connected in loop circuit with the field winding of the power generator and the armature of the regulating generator and including a pattern field 10 winding connected solely to an external source of electrical energy to cause the regulating generator to energize the power generator field winding.
